UNITED STATES PATENT OFFICE.

JAMES H. WALLACE AND ARTHUR G. HILTON, OF PROVIDENCE, RHODE ISLAND, ASSIGNORS TO THE INTERNATIONAL BURGLAR PROOF SASH BALANCE AND LOCK COMPANY, INCORPORATED, OF SAME PLACE.

SASH-BALANCE.

SPECIFICATION forming part of Letters Patent No. 678,600, dated July 16, 1901.

Application filed June 7, 1900. Serial No. 19,406. (No model.)

To all whom it may concern:

Be it known that we, JAMES H. WALLACE and ARTHUR G. HILTON, citizens of the United States, residing at Providence, in the county 5 of Providence and State of Rhode Island, have invented a new and useful Improvement in Sash-Balances, of which the following is a specification.

In windows the wood of the sash and the 10 frame is liable to shrink and to warp, the window-sash becomes loose in the frame, and if the sash is balanced by a spring-controlled gear engaging with a rack the shrinkage and the warping of the wood change the adjustment 15 between the gear and the rack and interfere with the proper balancing of the sash and the secure locking of the same.

This invention has reference to an improvement 20 in a sash-balance; and it consists in the peculiar and novel construction and the combination of parts whereby the sash-balance and the locking device may adjust themselves to the varying conditions as also to peculiar 25 conditions of the window-casing.

Figure 1 is a vertical sectional view of the 30 window-casing and sash-balance, showing the sash provided with a rack. Fig. 2 is a transverse sectional view of the same on the line X X of Fig. 1. Fig. 3 is an enlarged transverse sectional view of the lower part of the 35 casing, showing the detent-operating arm and the shaft-bearings formed in the two-part casing. Fig. 4 is a perspective view of the stop or detent operating means, and Fig. 5 is a perspective view of a modified form of the same.

Similar marks of reference indicate corresponding parts in all the figures.

In the drawings, *a* indicates the window-frame, *a'* the window-sash, and *a²* the rack secured to the window-sash. The face-plate *b* is secured to the window-frame and is provided with bracket *b'*, with which the casing *b²*, inclosing and supporting the mechanism of the sash-balance, is pivotally connected. The concave guard-plate *b³* extends from the face-plate *b* rearward and forms a guide for the lower corner of the casing *b²*. The casing is cast in two parts, the bearings for the

rocking shaft of the locking-detent and the 50 screw *b⁴* being formed in the brackets *b⁵* *b⁵* and in the abutment *b⁶*, so that when the two parts of the casing are secured together by the screws *b⁷* *b⁷* the screw *b⁴* and the rock-shaft *b⁸* are held in place. 55

The gear *c*, which, as is usual in sash-balances, contains and is actuated by a helical spring, is journaled on bearings supported by the casing *b²*, and the casing is held by a yielding spring-pressure to the face-plate *b*. 60 The screw *b⁴* is held between the two parts of the abutment *b⁶* with a loose sliding fit. The screw engages with the nut *b⁹*, which, bearing against the flat surface in the lower part of the casing *b²*, is held against rotation. The 65 coiled spring *b¹⁰* surrounds the screw and bears against the abutment *b⁶* and the nut *b⁹*. The head of the screw *b⁴* loosely fits the countersunk recess in the face-plate, so as to permit of slight oscillating motion. The tension of 70 the spring *b¹⁰* is adjusted by the screw *b⁴*, and the resiliency of the spring tends to hold the casing *b²* against the face-plate *b* and the gear *c* in mesh with the rack, so that the gear can adjust itself automatically and follow any 75 irregularities of the rack.

The locking device consists of the detent *c'*, projecting from the rock-shaft *b⁸*. The detent may project radially from the rock-shaft, as shown in Fig. 4. It may be offset 80 to one side, as shown in Fig. 5, or arranged in any other suitable manner, so that by rocking the rock-shaft the detent may enter between the teeth of the gear *c* to lock the gear or removed from between the teeth to unlock 85 the gear. The rock-shaft is provided with a groove. The arm *c²* or the bracket *c³* has a sliding fit on the rock-shaft *b⁸*. Either may be used to suit peculiar conditions that may require a push-button for operating the locking devices to be placed into abnormal positions. The screw *c⁴* connects the arm with the rock-shaft and allows the arm to slide on the rock-shaft to the desired position, while the casing swings with the variations of the 95 rack.

The member *c⁵*, preferably bifurcated, is pivotally connected with the arm *c²* or bracket

c³. The opposite end is screw-threaded to receive the end of the actuating-rod *c⁶*, which extends through one of the slots *c⁷*, formed, preferably, in both sides of the casing *b²*, and 5 through the frame to the outside of the window-casing *a⁸*, where it connects with any suitable operating device, usually a spring-pressed push-button.

By the use of the sliding connection of the 10 arm *c²* on the rock-shaft *b⁸* and the slot *c⁷* in the casing *b²* the actuating-rod may be located in any desired position. Moldings on the window-casing may be avoided.

In the preferred form the two sides of the 15 casing *b²* are connected pivotally by the bolt *a⁴*, as is shown in Fig. 2.

Having thus described our invention, we claim as new and desire to secure by Letters Patent—

20 1. In combination with the window-sash rack, the gear engaging with the rack, and the casing inclosing the gear, of a rock-shaft longitudinally grooved, a detent on the rock-shaft adapted to engage with the gear to lock 25 the same, an arm connected with the rock-shaft and free to slide on the same, a member pivotally connected with the arm on the rock-shaft and adapted to receive the actuating-rod, and a slot in the side of the casing 30 on a line with the actuating-rod, whereby the actuating-rod may be located at any desired place on the window-casing, as described.

2. In a window-sash-controlling device of the nature described, the combination with 35 the gear, of a detent connected with a rock-shaft, a slot in the casing inclosing the mechanism and actuating mechanism connected with the rock-shaft by a longitudinal groove-and-spline engagement, whereby the lock-ac- 40 tuating mechanism may be adjusted on the

rock-shaft to any desired position, as described.

3. In a window-sash-controlling mechanism of the nature described, the combination with the rack on the window-sash, the face-plate 45 on the window-frame, and the gear, of a casing forming the support of and inclosing the mechanism, a pivotal connection of one end of the casing with the face-plate, a spring-actuated yielding connection of the other end 50 of the casing with the face-plate, a slot in the side of the casing, and a locking device, consisting of a rock-shaft, a detent on the rock-shaft adapted to engage with the gear, an arm connected with the rock-shaft by a groove-and- 55 spline connection, and means for operating the arm, whereby the gear and the casing may follow the changed or changing positions of the rack and the arm slide on the rock-shaft without affecting the mechanism for operating the locking devices, as described.

4. In a sash-balance, the combination with the gear *c* and the inclosing casing *b*, of the slot *c⁷* in the casing *b²*, the actuating-rod *c⁶* in screw-thread engagement with the member *c⁵*, 65 the member *c⁵*, the arm *c²* pivotally connected with the member *c⁵*, the screw *c⁴* in the arm *c²*, the rock-shaft *b⁸* having a longitudinal groove with which the screw *c⁴* in the arm *c²* engages, and a detent connected with the 70 rock-shaft and adapted to engage with the gear to lock the same, as described.

In testimony whereof we have signed our names to this specification in the presence of two subscribing witnesses.

JAMES H. WALLACE.
ARTHUR G. HILTON.
